UNITED STATES PATENT OFFICE.

SAMUEL W. HUDSON, OF HUDSONDALE, PENNSYLVANIA.

WATER-ELEVATOR.

SPECIFICATION forming part of Letters Patent No. 278,796, dated June 5, 1883.

Application filed December 27, 1882. (No model.)

To all whom it may concern:

Be it known that I, SAMUEL W. HUDSON, of Hudsondale, in the county of Carbon and State of Pennsylvania, have invented certain new and useful Improvements in Water-Elevators, of which the following is a specification.

In the accompanying drawings, Figure 1 is a diagrammatic sectional elevation of my improved organization, and Fig. 2 a similar view of a modified organization.

I have represented my invention somewhat diagrammatically organized for practical working, and I regard the arrangement there shown as a very efficient one, though, so far as the leading feature of the invention is concerned, which is hereinafter described and specifically claimed, the details shown may be varied without departing therefrom.

Pipes A A lead from the water to be elevated to the bottoms of the chambers B C, the entrances into the chambers being covered by inwardly-opening flap-valves a a. Depending pipes a' a' extend from the bottoms of the pumping or water-elevating chambers D and E down into the chambers B C, and serve to place these compartments in communication. The entrances from the pipes a' into the chambers D E are also closed by inwardly-opening flap-valves a'. Pipes F F, into which the water to be elevated, as hereinafter described, is forced, communicate with the chambers D and E at or near their bottoms, the openings between the chambers and the pipes being covered by flap-valves f opening into the pipes. A valve-chest, G, located above the cylinders D and E, has two ports, g and h, and a suitable slide, i, operated by a shaft, i'. The port g communicates with the pumping-chamber D and the opposite lower chamber, C, while the port h communicates with the pumping-chamber E and the opposite lower chamber, B. The valve-chest has also a central port, k, which can be thrown into communication with either of the ports g or h by the operation of the valve-slide, and is in permanent communication, by means of a pipe, l, with the central port of the valve-chest M of the air-compressor N. The valve-chests M and G are in permanent communication by means of a pipe, o. The air pumping and compressing

apparatus N is driven by a suitable motor, P, P, a steam-motor being indicated in the drawings.

With the valve-slide i thrown over to one side, 55 it will be obvious that the air in one of the upper chambers, D or E, and the opposite lower chamber will be pumped out and driven into the other upper chamber and its corresponding opposite lower one. Thus, with the slide i in 60 the position shown in the drawings, the port g, which is in communication with the upper chamber D and the lower chamber C, is in communication with the pipe l and the central port of the valve-chest M, so that when 65 the steam-engine is working, the piston of the air pump and compressor reciprocated, and its slide-valve operated, the air will be taken from the chambers D and C and forced into the chambers E and B through the valve-chest M, 70 pipe o, valve-chest G, and port h. With the apparatus thus working, the air in the chambers D and C will be exhausted and compressed into the chambers E and B. The effect of this will be that the vacuum or partial vacuum 75 created in the chamber C will cause the water to be elevated to rise therein, and, supposing a similar operation to that just described to have previously occurred, with the valve-slide i thrown over to the right, or in the opposite 80 position to that indicated in the drawings, the water, which by that means would have been raised into the chamber B, will now rise into the chamber D on account of the vacuum produced therein, as above described, and also 85 on account of the pressure in the chamber B, which latter point will presently be more particularly referred to. With the apparatus in the condition shown in the drawings, the chambers D and C therefore will be full or par- 90 tially full of water, which will be sustained therein by the flap-valves. If, now, the valve-slide i be shifted so as to place the chambers E and B in communication with pipe l, it will be obvious that the air in those chambers will 95 be pumped out and compressed in the chambers D and C. The effect of the pressure in the chamber D will be to force the water out of that chamber and elevate it through the pipe F to the desired point, while the combined 100 effect of the vacuum or partial vacuum in the chamber E and the pressure in the cham-

ber C will be to cause the water to rise and fill the chamber E, so that it will be driven out by the compressed air into the pipe F, when the action of the machine is reversed by again shifting the valve-slide *i*.

Many ways may be devised of automatically operating the valve-slide shaft *i* so as to give a continuous successive operation, such as described, when the engine P is running.

10 I have illustrated in the drawings, and will now describe, what I consider the simplest and most efficient means of effecting the reversal of the valve-slide.

A hollow elongated bucket, *r*, is suspended 15 in each of the chambers D E from a small piston-rod, *q*, which passes through suitable packing in the top of the chamber, and is pivoted to one arm of the elbow-lever *q'*, the other arm of the lever being connected with the valve-shaft *i'*. The connections between the lever and valve-rod and piston *q* are loose or slide joints, so as to permit the piston and shaft to move in right lines. This device operates in 20 the following manner: When the water rises 25 in one of the pumping-chambers—say E—it fills the elongated bucket, and, buoying it up, causes the piston *q*, by means of the elbow-lever, to thrust the valve-shaft toward the left, so that the air will be exhausted from the chambers D 30 and C and compressed into the chambers E and B. As the water is driven out of the chamber E a point will be reached where the float *r* will fall sufficiently far to reverse the valve-shaft and valve-slide and cause the apparatus 35 to exhaust the air from the chamber E, out of which a large portion of the water has been forced, and to compress it into the chamber D to drive out the water which has meanwhile risen therein.

40 When the apparatus is operated as thus far described, the amount of pressure that can be obtained is due to merely compressing the volume of air, which fills all four of the cylinders, into two of them, and of course the power 45 thus acquired would be very limited. In order to work the apparatus under a high pressure and elevate the water to a considerable height, I place a tension-valve, *s*, on each end of the air-compressor cylinder N. The tension-valves 50 illustrated are pin-valves, and their power is regulated by means of a coiled spring and nut, as will be clear upon an inspection of the drawings. These valves can be adjusted to any desired pressure—say ten pounds—that is, whenever, 55 in exhausting the chambers D and C or E and B, a vacuum of ten pounds is obtained, the tension-valves will open and admit air, so that upon a continued working of the apparatus a high degree of pressure may be accumulated in either 60 pair of chambers. The amount of this pressure—assuming the power of the engine to be sufficient for all purposes—will depend upon the height to which the column of water in the pipe F is to be lifted—that is, the tension-valves will admit air and the engine will compress it until the power is sufficiently great to

drive the water out of the chamber and elevate it in the pipe F, and when the water in the chamber has been forced down to such a level as to cause the float to shift the valve-slide the tension-valves will immediately cease to operate, and as the highly-compressed air will be pumped into the other pair of chambers, and unless there has been some leakage, this volume of air will be just sufficient to elevate the column of water from this lifting-chamber. In case of any leakage, however, the tension-valves will of course admit air until the required pressure to elevate the water is obtained, the amount of compression in all cases being proportional to the height to which the column of water is to be elevated.

By the organization of the apparatus described water can be elevated to very great heights. Thus the water is raised by vacuum 85 into the chambers B and C, and from these chambers is raised by the combined action of pressure and vacuum into the lifting-chambers D and E before the final lift due to the direct compression of the air is exerted. If the apparatus is working at a vacuum of, say, ten pounds, the chambers B and C may be twenty feet or more in length, and the water will rise to about fill them, and with a combined pressure and vacuum to raise the water into the chambers 95 D and E it may be lifted a considerable height. When to this elevation the height of the final lift due to the direct compression of the air is added the water will be elevated to a comparatively great height. By this organization I 100 am enabled to elevate water with a very marked economy of power; or, in other words, by the use of such an apparatus as I have described I can with a given power elevate a column of water to a greater height than it has been possible to do heretofore.

As above remarked, many of the details of this organization may be varied without departing from the broad principle of the invention, and some portions of the organization 110 may be used without the others. For instance, the chambers B and C might be dispensed with, and the apparatus organized so as to operate with simply two chambers, D and E, alternately producing a vacuum in one and a pressure in the other; and, as above mentioned, the means of effecting the shifting of the valve-slide may be changed without departing from the leading feature of my invention. For instance, under the organization shown in Fig. 2, 115 where the chambers B and C are dispensed with, the shifting of the valve-shaft *i* may be effected by means of the pressure in one of the cylinders and the vacuum in the other, in the following manner: The valve-shaft *i* passes through two 120 small cylinders, T, one on each side of the valve-chest, and carries piston-heads which work in these cylinders. The cylinders communicate at their inner ends by means of passages *t* with the chambers D and E, while the opposite ends are in communication with the atmosphere by openings *t'*. The shaft *i* may be

adjusted in any suitable manner, so as only to move when a given force is applied to it. When the apparatus is working with the parts in position shown in this figure, so that a vacuum will be produced in D and a pressure in E, it will be noted that as the force of the pressure in E increases the power of the vacuum in D will also increase, and that the pressure in E through the opening *t* will operate in the right-hand cylinder T to thrust the piston-head over and shift the valve-shaft, while the power of the vacuum in the opposite cylinder T will operate in conjunction with the pressure, as will be plain from the drawings. When, therefore, the combined pressure and vacuum exert the required power, the valve-shaft will be shifted and the operation reversed, as will be well understood. The shaft may also be worked by a single cylinder, the piston being shifted alternately by pressure and vacuum. This will be plain, and needs no description.

The right is reserved to hereafter file another application or applications for the subject-matter illustrated in Fig. 2; or for any subject-matter herein described or illustrated and not claimed.

What I claim as my invention is—

1. The combination, substantially as set forth, of the two water-elevating chambers, air pumping and compressing mechanism for alternately exhausting the air from one chamber and compressing it in the other, valve mechanism for accomplishing such successive

operations, and floats in the water-elevating chambers, which automatically work the valve mechanism with which they are directly connected.

2. The combination, substantially as set forth, of the chambers B and C, the water-elevating chambers D and E, the connecting pipes and valves, the valve mechanism G, the air pumper and compressor and its valve mechanism, a motor for driving the pumping and compressing mechanism, water-elevating pipes or conduits, and means for automatically shifting the valve-slide *i*.

3. The combination, substantially as set forth, of the water-elevating chambers, air pumping and compressing mechanism for alternately exhausting the air from one chamber and compressing it in the other, valve mechanism for automatically causing such alternate successive operation, means for operating the valve mechanism, water-elevating pipes or conduits, and an air-inlet tension valve or valves.

4. The combination, substantially as set forth, of the chambers B D and C E, the connecting-pipes, valve mechanism, and air pumper and compressor.

In testimony whereof I have hereunto subscribed my name.

SAMUEL W. HUDSON.
